US0D1060687S

(12) **United States Design Patent** (10) **Patent No.:** **US D1,060,687 S**
(45) **Date of Patent:** **** Feb. 4, 2025**

(54) **FINGER STRETCHER**

(71) Applicant: **Baosheng Hu**, Hangzhou (CN)

(72) Inventor: **Baosheng Hu**, Hangzhou (CN)

(**) Term: **15 Years**

(21) Appl. No.: **29/912,005**

(22) Filed: **Sep. 12, 2023**

(30) **Foreign Application Priority Data**

Aug. 28, 2023 (CN) 202330552082.0

(51) **LOC (15) Cl.** **24-02**

(52) **U.S. Cl.**

(57) **CLAIM**

The ornamental design for a finger stretcher as shown and described.

DESCRIPTION

FIG. 1 is a perspective view of a finger stretcher showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the finger stretcher that form no part of the claimed design.

1 Claim, 8 Drawing Sheets
